GARMENT BOX

Carl W. Sundberg, Bloomfield Hills, Mich., assignor to Gerald P. Kent, Southfield Township, Mich.

Filed Aug. 30, 1960, Ser. No. 61,958

Term of patent 14 years

(Cl. D58—12)

FIG. 2 is a side elevational view thereof;

FIG. 3 is an end elevational view taken from the left of FIG. 1;

FIG. 4 is a sectional view of the top of the box shown in FIG. 1 and taken along the line 4—4 thereof; and

FIG. 5 is an enlarged fragmentary detailed view thereof.

The dominant features of my design reside in the portions shown in full lines.

I claim:

The ornament design for a garment box, as shown and described.
